BY *Frank J. Moore*

ATTORNEY

UNITED STATES PATENT OFFICE.

SIMON BOLLINGER, OF SOUTH WHITLEY, INDIANA.

STOVEPIPE-THIMBLE.

SPECIFICATION forming part of Letters Patent No. 700,611, dated May 20, 1902.

Application filed January 14, 1902. Serial No. 89,668. (No model.)

To all whom it may concern:

Be it known that I, SIMON BOLLINGER, a citizen of the United States, residing at South Whitley, in the county of Whitley and State of Indiana, have invented certain new and useful Improvements in Stovepipe-Thimbles, of which the following is a specification.

My invention relates to improvements in stovepipe-thimbles; and one object of my invention is the provision of means which will make a neat and tight connection of the stovepipe with the flue-opening.

Another object of my invention is the provision of a stovepipe-thimble which will not mar or disfigure and which will be of inexpensive, durable, and practical construction and entirely efficient for the purpose designed.

With these objects in view my invention consists of a stovepipe-thimble embodying novel features of construction and combination of parts, substantially as disclosed herein.

Figure 1 represents a perspective view of my thimble or cap applied in position to a chimney. Fig. 2 represents a horizontal sectional view of the device on line 2 2 of Fig. 3 to show its novel construction and arrangement of parts. Fig. 3 represents a vertical sectional view, and Fig. 4 represents a similar view taken on line 4 4 of Fig. 3 through the clamping ring or band. Fig. 5 represents a detail perspective view of the hood or cover detached.

In the drawings, A designates the chimney or flue provided with the stovepipe-opening B, and in this opening fits my thimble, which consists of the split pipe-section or sleeve C, having its outer portion provided with flange D, and said outer portion projects slightly beyond the flue and around the projecting outer portion fits the clamping ring or band E, formed with the ears F, through which passes the adjusting or clamping screw G, and to cover the ears I provide the hood or cover H, which is provided with the inward-extending lip J, which fits over the clamping-screw and holds the cap in place and makes a neat-appearing joint.

Surrounding the thimble and retained in

place thereby is the circular plate K, and the split ends of the thimble each are provided with the guides or cleats L, in which fits the wedge-shaped plate M, the purpose of which is to spread the ends of the thimble and adjust them to the flue-opening or to accommodate the stovepipe and to secure the ends of the thimble and also to permit the easy removal of the thimble when found necessary.

The clamping-band, it will be seen, serves to retain the end of the pipe away from the disk, also holds the pipe properly and prevents the wedge-shaped plate M from working loose. In fact, the band acts to hold the parts in proper place and gives an ornamental appearance to the device.

It will be noticed that my thimble is short and only occupies the width of the flue; also that it can be easily applied or detached, as circumstances require, that it makes a perfect connection for the stovepipe, and that it is of neat and attractive appearance and will not mar or disfigure the chimney, and that it is thoroughly efficient in other respects.

I claim—

1. A stovepipe-thimble, composed of the circular plate or disk, the pipe-section or sleeve passing therethrough and having its ends split, the adjusting-plate carried by said ends, the ring or band surrounding the projecting end of the thimble, the adjusting devices for said band, and the cap or cover secured over and upon the adjusting devices and having a portion engaging the adjusting-bolt to secure the cover in place.

2. A stovepipe-thimble, consisting of the split pipe-section or sleeve, the adjusting-plate engaging the split portions of the sleeve, the band surrounding the split sleeve and having an adjusting-bolt engaging its free ends, and a cover having a lip engaging the bolt to secure the cover over the adjusting devices.

In testimony whereof I affix my signature in presence of two witnesses.

SIMON BOLLINGER.
